UNITED STATES PATENT OFFICE.

ALBERT A. PAGE, OF EAST HAVEN, CONNECTICUT, ASSIGNOR TO SARGENT & COMPANY, OF NEW HAVEN, CONNECTICUT, A CORPORATION OF CONNECTICUT.

LOCK.

1,237,948.

Specification of Letters Patent. Patented Aug. 21, 1917.

Application filed October 20, 1916. Serial No. 126,717.

To all whom it may concern:

Be it known that I, ALBERT A. PAGE, residing in East Haven, county of New Haven, State of Connecticut, have invented 5 certain new and useful Improvements in Locks, of which the following is a full, clear, and exact description.

This invention relates to locks, and more particularly to indicator locks which are especially adapted for use on hotel corridor doors, having means for indicating to a chamber-maid or other person on the outside of the door whether or not the room is occupied by the guest. The invention 10 also pertains especially to a lock structure wherein the indicator is carried by the jamb of the door, and wherein such indicator can be read by feeling or touch, so that it is as useful at night as in the day time.

20 One of the primary objects of the invention is to provide an indicator of the above described nature in connection with a lock of the so-called one-bolt type, that is to say, a lock having a single dead bolt 25 which may be protracted from either side of the door.

Another object of the invention is to provide a lock structure having a special indicator bolt adapted to coöperate with an 30 indicating device on the door jamb, which indicator bolt is projected concurrently with the main locking bolt when the latter is actuated from one side of the door, whereas said indicator bolt is not actuated when 35 the locking bolt is projected from the opposite side of the door. Thus, when the door is locked from one side, the indicator on the jamb is actuated in a certain way, but it is not so actuated when the door is 40 locked from the opposite side. Hence, it is possible to obtain an indication as to the side of the door from which the bolt has been projected, and as to the occupancy or non-occupancy of the room.

45 Another object of the invention is to provide a lock in which two bolts are projected concurrently from one side of the door, whereas only one bolt is projected by the change key from the opposite side of the 50 door.

To these and other ends, the invention consists in the novel features and combinations of parts to be hereinafter described and claimed.

In the drawings,

55 Figure 1 is a front elevation of a door and door frame equipped with a lock embodying my invention, showing the door locked from the inside;

Fig. 2 is a horizontal section through certain parts shown in Fig. 1;

Fig. 3 is a similar view, showing the position of the parts when the door is locked from the outside by the change key;

Fig. 4 is a face view of the strike and 65 the indicator associated therewith;

Fig. 5 is an elevation of the upper part of the lock proper, with the cap plate removed, showing the main locking bolt and the indicator bolt in the retracted positions;

70 Fig. 6 is a similar view, showing the position of the parts when the locking bolt is projected from the outside of the door by the change key;

Fig. 7 is an elevation of the entire lock, 75 showing the position of the parts when the locking bolt is shot from the inside of the door by the thumb turn; and

Fig. 8 is a longitudinal section through the cylinder lock, with the change key inserted therein and turned to actuate the locking bolt.

In the particular form shown, the door 10 is mounted in a casing 11, having the usual door jamb 12, and said door is 85 equipped with a mortise lock having a case 13 and a latch bolt 14 adapted to be retracted by the usual knob mechanism 15. A locking bolt 16 in the case 13 is adapted to be actuated from the outside of the door 90 by a cylinder lock 17, having a series of keys, and this locking bolt 16 may be actuated from the inside of the room by means of a thumb turn or the like (not shown). When operated by a thumb turn, the lock 95 is equipped with a thumb turn hub 18 for actuating the locking bolt. The latter bolt locks the door by engaging an opening 20 in a strike 21 mortised in the usual way in the door jamb, and the latch bolt 14 is, in 100 this particular instance, adapted to engage the lower portion 20^a of the strike opening. Mounted between the latch bolt and the locking bolt is a special indicator bolt 22, which when projected is adapted to extend into 105 the elongated strike opening 20 at the intermediate part thereof, and at this intermediate portion of the strike opening is lo-

cated an indicator operating lever 23 lying back of and transversely to said opening and adapted to be engaged by the head of the bolt 22 in the manner shown in Fig. 2. In the present embodiment, the lever 23 is mounted at the back of a special angular plate 24 mortised in the door jamb at the outside of the door. The lever 23 is pivoted horizontally on this plate by means of a pivot pin 25, said pivot pin located between the ends of said lever so that when the inner end 23^a of the lever is shifted by the protraction of the bolt 22 in a direction away from the edge of the door, the opposite end 23^b of said lever is shifted in the opposite direction. When so shifted, the end 23^b of the lever engages and pushes outward an indicator plunger 26 mounted to slide in the plate or member 24. This plunger 26 is mounted in a suitable socket and surrounded by a spring 27 which is normally extended so as to hold the outer end of the plunger substantially flush with the outer face of the plate or mounting 24, as shown in Fig. 3. When, however, the indicator bolt 22 is projected, as shown in Fig. 2, the lever 23 causes the plunger to be thrust outward in opposition to the spring 27, and in this manner the end of the plunger is caused to protrude from the plate 24, as shown in Fig. 2, thus providing an indicator which is adapted to be felt by the hand from the outside of the door. When the indicator is set in the position shown in Fig. 2, the chambermaid can readily determine by running her hand down the jamb of the door whether or not the plunger is in the extended position. When the plunger stands in one position, she will know that the indicator bolt has been thrown from the inside, and if it stands in another position she will know that the indicator bolt has not been projected. The arrangement of the lock parts is such that when the locking bolt is projected from one side of the door, the indicator bolt is actuated, whereas when the locking bolt is projected from the opposite side of the door the indicator bolt remains stationary in its retracted position; and therefore the position of the plunger 26 indicates whether or not the room is occupied.

In the present embodiment, the lock parts are so arranged that both the locking bolt and the indicator bolt are projected from the inside of the room by actuation of the thumb turn hub 18, and when the indicator bolt is projected the indicator plunger 26 is projected out of the door jamb in a line substantially parallel to the outer face of the door, so that it can be readily felt by the chambermaid. When, however, the locking bolt 16 is projected from the outside of the door by the change key, the indicator bolt 22 remains stationary in its retracted

position, and therefore the manual test indicator 26 is not actuated, but, on the other hand, remains with its outer end or face substantially flush with the surface of the door jamb, so as not to present any projection on the jamb. Thus, when the jamb is smooth and devoid of any projection, the chambermaid knows that the door has been locked from the outside, and that the room of the guest is unoccupied.

The means for actuating the locking bolt and the indicator bolt in the manner above described may be substantially as follows:

The locking bolt 16 has a shank of usual form suitably guided on the back of the case. This shank is provided with a pair of talons 28 adapted to be engaged by a cam arm or rollback 29 on the cylinder lock 17 previously mentioned, when the cylinder lock is actuated by the change key 29^a (Fig. 8) from the outside of the door. A primary tumbler 30 is bodily carried by the bolt 16, being pivoted thereto at 31. This tumbler has a lug 32 adapted to coöperate in the usual manner with the fence or stump 33 on the case so as to lock the bolt either in the projected or the retracted position. At the rear extremity of the tumbler 30, the same is provided with a loop 34 which embraces and clears the thumb turn hub 18 with its wings 18^a; and on the upper part of the loop 34 is a projection 35 which lies between the talons 28 and is adapted to be engaged by the rollback 29 in the usual manner.

The indicator bolt 22, which is mounted below the deadbolt, has a flat shank suitably guided for reciprocation in a line parallel to the locking bolt, and is adapted, under some circumstances, to protract the locking bolt by means of the thumb turn hub 18. The shank 36 of the indicator bolt carries near the head of said indicator bolt an upwardly projecting shoulder 37, which engages a recess in the shank of the locking bolt. When the parts occupy the position shown in Fig. 5, this shoulder 37 engages the forward edge of the recess in the locking bolt so that the latter may be protracted by the forward movement of the indicator bolt. The shank 37 of the indicator bolt carries a pin 38 on which is mounted a secondary tumbler 39. The secondary tumbler 39 is adapted to be actuated by the thumb turn hub 18, for which purpose said tumbler is provided with a pin 40 located between the wings of the thumb turn hub. The tumbler 39 coöperates with a fence 41 (see Fig. 7) cast on the back of the lock case, which is adapted to hold said tumbler and thereby the connected indicator bolt, either in the retracted position shown in Fig. 5, or the protracted position shown in Fig. 7. A lug 42 on the intermediate portion of the secondary tumbler is located

above a hook 43 depending from the primary tumbler 30, the arrangement being such that the depression of the secondary tumbler by the thumb turn hub will cause a corresponding depression of the primary tumbler so as to disengage the latter from the fence or stump 33.

When the guest wishes to lock his room against intrusion, he turns the thumb turn hub 18 by means of the thumb turn, and this depresses the secondary tumbler (releasing it from the fence 41), which tumbler in turn depresses the primary tumbler through the connection 43, 42, and then when the primary tumbler has been pulled out of engagement with the fence 33, the continued rotation of the hub will push the secondary tumbler forward, carrying with it the indicator bolt 22. The shoulder 37 on the indicator bolt engages the lower portion of the shank of the locking bolt and thereby the locking bolt is protracted concurrently with the indicator bolt. The head of the indicator bolt may be of cylindrical form, as shown, and it need not be of any great area to actuate the indicator plunger properly in the manner hereinbefore described. As the thumb turn is turned in the opposite direction, the bolts 22, 16 are released, and the locking bolt is pulled back with the indicator bolt by means of the abutment of hook 43 against the lug 42. When the rollback 29 of the cylinder lock 17 is actuated by the change key 29^a from the outside of the room, the indicator bolt is not actuated because the rollback depresses the primary tumbler individually, thereby carrying the hook 43 out of coöperation with the lug 42, and the locking bolt is projected by the rollback independently, as shown in Fig. 6.

Various changes may be made in the details of the construction without departing from the scope of the invention as defined in the claims.

It will be observed from Fig. 7 that when the indicator bolt 22 is protracted, the latch bolt 14 cannot be retracted by the knob mechanism as the sliding forward of the indicator bolt rocks a dog 14^a into locking engagement with the knob shoe 14^b as shown in the Sparks Patent No. 1141984, dated June 8, 1915. In this manner, rotation of the outside knob is prevented when the door is bolted from the inside, but when the door is bolted from the outside by the change key, the knob remains free because the indicator bolt is not protracted, and does not therefore move the dog 14^a to its operative position.

When I refer to the indicator mechanism being inoperative when the locking bolt is protracted from one side of the door, *e. g.*, the outside, I mean that it is inoperative by the change key or other equivalent means usually employed for protracting the bolt,

as distinguished from a special shut out key. Such a shut out key may, and usually does, actuate the indicator in the same way as the latter is actuated by the thumb turn mechanism, but the shut out key is used so seldom that it does not detract appreciably from the value of the indication given by the indicator mechanism.

What I claim is:—

1. The combination with a door and door frame, of a lock on the door having a dead bolt, a strike on the frame to receive said bolt, said lock having means for protracting said bolt from either side of the door, an indicator device on the door frame at the outside of the door, and setting means for said indicator device operated automatically on the protraction of said bolt from one side of the door, said setting means being inoperative by the protraction of said bolt from the opposite side of the door; substantially as described.

2. The combination with a door and door frame, of a lock on the door having a locking bolt, a strike on the frame to receive said bolt, the latter being protractable from either side of the door, an indicator plunger on the door frame, and means for operating said indicator plunger automatically as said bolt is projected from one side of the door, said plunger inoperative as said bolt is projected from the other side; substantially as described.

3. The combination of a door and door frame, a lock on the door having a bolt, said bolt protractable from either side of the door, a strike on the frame to receive said bolt, a manual test indicator on the door frame at the outside of the door, and means for operating said indicator when said bolt is projected from the inside of the door, said indicator inoperative when said bolt is projected from the outside; substantially as described.

4. The combination with a door and door frame, of a locking bolt on the door, an indicator bolt on the door, a strike on the door frame to receive said bolts, means for projecting both bolts concurrently from one side of the door, indicator means on the door frame operative by said indicator bolt, and means for projecting the locking bolt independently of the indicator bolt from the opposite side of the door; substantially as described.

5. In a lock, the combination of a case, a locking bolt therein, an indicator bolt therein, both of said bolts adapted to project exteriorly of said case, thumb turn mechanism for so projecting said bolts, key mechanism for projecting the locking bolt independently, a strike to receive said bolts, and indicator mechanism associated with the strike and adapted to coöperate with said indicator bolt; substantially as described.

6. The combination with a door and door jamb, of a lock on the door having two bolts, a strike on the door jamb to receive said bolts, means at the outside of the door for indicating the protraction of one of said bolts, means at the outside of the door for protracting the other bolt independently of said last-named bolt, and means at the inside of the door for protracting both bolts simultaneously; substantially as described.
7. The combination with a door and door jamb, of a lock on the door having two dead bolts, keeper means for said bolts mounted on the door jamb, means on the door jamb at the outside of the door for indicating the protraction of one of said bolts, key mechanism for protracting the other of said bolts from the outside of the door independently of said last-named bolt, and thumb turn means for protracting both bolts concurrently from the inside of the door; substantially as described.
8. The combination with a lock having a bolt protractable exclusively from the inside, a second bolt protractable from either side, and means for protracting both bolts simultaneously from the inside, of a manual test member on the door frame at the outside of the door, and means for setting said test member by the protraction of said first bolt; substantially as described.
9. In a lock, a key bolt, key mechanism for protracting said bolt from the outside of the door, a change key for operating said key mechanism, thumb turn means for protracting said bolt from the inside of the door, a manual test member at the outside of the door, and means inoperative when said bolt is protracted by said change key for shifting said manual test member bodily and automatically when the bolt is protracted by said thumb turn mechanism; substantially as described.
10. The combination with a door and door frame, of a lock on the door having a bolt protractable from either side of the door, an indicating device mounted on the door frame, and means, inoperative when said bolt is protracted from one side of the door, for actuating said indicator automatically when the bolt is protracted from the opposite side; substantially as described.
11. In a lock, the combination of a bolt protractable from either side of the door, a sliding indicator plunger at the outside of the door, and means, inoperative when said

bolt is protracted from the outside of the door, for moving said indicator plunger outward into a predetermined projecting position when said bolt is protracted from the inside; substantially as described.

12. In a lock, a locking bolt protractable from either side of the door, a latch bolt, knob mechanism for retracting said latch bolt from the outside of the door, an indicator at the outside of the door, and means, inoperative when said locking bolt is protracted from the outside of the door, for setting said indicator and dogging said knob mechanism automatically when said locking bolt is protracted from the inside; substantially as described.

13. In a lock, a locking bolt protractable from either side of the door, a latch bolt, knob mechanism for retracting said latch bolt from one side of the door, a manual test indicator at the last-named side of the door, and a single member, inoperative when said locking bolt is protracted from one side of the door, for dogging said knob mechanism and for shifting said manual test indicator automatically on the protraction of said locking bolt from the opposite side; substantially as described.

14. The combination with a door and door frame, of a lock on the door having a bolt, a strike on the frame to receive said bolt, means for protracting said bolt from the outside of the door by a key, thumb turn means for protracting said bolt from the inside of the door, an indicator on the door frame, and an operating device associated with said lock, but inoperative when said bolt is protracted by said key, for setting said indicator automatically on the protraction of said bolt by said thumb turn means.

15. The combination with a door and door frame, of a dead bolt on the door, a strike on the frame to receive said bolt, a key for protracting said bolt from the outside of the door, thumb turn means for protracting said bolt from the inside of the door, an indicator on the door frame at the outside, and means for shifting said indicator automatically on the protraction of said bolt by the said thumb turn means, said indicator being immovable by the protraction of said bolt by said key.

In witness whereof, I have hereunto set my hand on the 13th day of October, 1916.

ALBERT A. PAGE.
